(57) **CLAIM**

The ornamental design for an electric connector housing as
shown and described.

DESCRIPTION

FIG. 1 is a top, front and right perspective view of an electric connector housing, showing the new design;

FIG. 2 is a bottom, front and left perspective view thereof;

FIG. 3 is a top, rear and left perspective view thereof;

FIG. 4 is a bottom, rear and right perspective view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is a right-side elevation view thereof; and,

FIG. 10 is a left-side elevation view thereof.

The broken lines shown in the Figures are included to show
environmental structure and unclaimed subject matter of the
invention and therefore form no part of the claimed design.
The thin, discontinuous lines in the drawings are surface or
contour lines for the purpose of demonstrating shape and are
not visible lines on the electric connector housing.
